UNITED STATES PATENT OFFICE.

CHARLES MELVIN DAVIS, OF LYNN, MASSACHUSETTS.

TERMINAL CONNECTER.

Application filed October 27, 1919. Serial No. 333,680.

To all whom it may concern:

Be it known that I, CHARLES MELVIN DAVIS, a citizen of the United States, and a resident of Lynn, in the county of Essex and Commonwealth of Massachusetts, have invented a new and useful Improvement in Terminal Connecters, of which the following is a specification.

The present invention relates to terminal connectors adapted to be clamped or secured to storage battery terminals.

Present-day commercial terminal connectors are adapted to be secured to battery terminals by wrenches or other tools operating upon nuts or the polygonal heads of bolts situated to one side of the connector. Owing to the enforced positioning of the wrench or other tool off to one side, the tool frequently comes accidentally into contact with several terminals or binding posts at once, causing a short-circuit and the destruction of the battery. After the nut or bolt becomes loosened, furthermore, the connector can not easily be dislodged from the terminal except by blows from a hammer or by prying the jaws of the connector open with some instrument, and after this is done, it is frequently found that the connector is no longer suitable for use with terminals of the same dimensions, though possibly fitting terminals of larger dimensions.

The object of the present invention is to improve the construction of terminal connectors, increasing their durability and efficiency and reducing their cost of manufacture.

With this end in view, a feature of the invention contemplates the provision of a terminal connector that shall be adapted to be clamped and unclamped from above the connector instead of from the side, thus eliminating the danger of short-circuiting the battery, which may be easily secured to, and removed from, a terminal, and which shall be adapted for use with terminals of various dimensions.

To the attainment of the above-mentioned object, the invention consists of the improved terminal connector hereinafter described, illustrated in the drawings and defined in the appended claim.

In the accompanying drawings, Fig. 1 is a plan view of a portion of a battery equipped with the improved terminal connector constituting the subject matter of the present invention; Fig. 2 is a side view of

the terminal connector, shown clamped to a battery terminal; Fig. 3 is a longitudinal sectional view of the terminal connector; and Figs. 4, 5 and 6 are side views of modifications.

The invention is shown in Fig. 1 in its preferred form as secured to a terminal or binding post 2 of a storage battery 4 having, besides the terminal 2, binding posts 6 connected by connecting bars 8. The connector comprises a longitudinally extending body conducting member 10 having an opening 11 a wall of which constitutes an outer terminal-engaging jaw 12 and an inner cam or wedge face 14, and a conducting member 16 movable relatively to the body member and having an inner terminal-engaging jaw 18 and an outer cam or wedge face 20. The jaws 12 and 18 will hereinafter be referred to as cylindrical, using the term in the sense that storage-battery terminals, as ordinarily constructed, are cylindrical. Relative movement of the members in a line at right angles to the jaws 12 and 18 is effected through the operation of a wrench or other tool upon a polygonal head 22 provided upon a screw-threaded member 26 near the face 24 of the member 16. The screw-threaded member 26 is mounted in an opening 28 of the body member 10 and in an elongated opening 30 provided in the member 16 and registering with the opening 28. The screw-threaded member may be a screw screwed into the body member, as shown in Fig. 5, in which event the head 22 may be a separate nut, or the head and screw may be integral, as shown in Figs. 1 to 4 inclusive, or the head 22 of Figs. 1 to 4 inclusive may be slotted to provide for its operation by a screw driver, as shown in Fig. 6, or any other equivalent means may be employed for effecting the relative movement of the members 10 and 16. The head 22, by pressing in upon the face 24 of the member 16, causes a movement of the member 16 towards the body member 10, the wedge faces 14 and 20 cooperatively engaging to move the jaw 18 toward the jaw 12, such movement being permitted by the free play of the screw-threaded member 26 in the elongated opening 30. The connector becomes thus clamped or secured to the terminal through the engagement therewith of the jaws 12 and 18.

The terminal 2 is adapted to enter the opening 11 of the connector through the face 32 that is oppositely disposed to the

face 24. The wrench or other tool may thus be applied near the face opposite to the face of entry of the terminal, above the connector, instead of to one side thereof. The danger of the tool accidentally coming into contact with the binding posts 6 or the connectors 8 while electrically connected to the terminal 2, thereby short-circuiting the battery, is thus eliminated. Upon the head 22 becoming loosened, furthermore, the member 16 may be readily lifted away from the body member 10, avoiding the necessity of hammering the connector off the terminal or prying the terminal-engaging jaws 12 and 18 open with an instrument. By reason of the nature of the wedge or cam faces 14 and 20, the jaws 12 and 18 may be caused to engage snugly terminals of various sizes.

The connector is provided with a socket 34 adapted to receive a conductor. The socket may extend longitudinally, as illustrated in Fig. 4, or at an angle to the body member, as shown in Figs. 1 and 2. The construction of Figs. 1 and 2 lends itself further to the prevention of short circuits, inasmuch as it renders it possible to lead conductors to the terminal longitudinally of the battery while maintaining the connector at right angles thereto, or at any other angle such that the connector is reasonably far removed from the binding posts 6.

What is claimed as new is:—

A storage-battery connector comprising two conducting members between which a storage-battery terminal is adapted to be clamped; the two conducting members being separate and distinct one from the other to permit lifting one of the conducting mem-

bers away from the other conducting member and thereby release the storage-battery terminal without hammering the connector or prying the connector away from the storage-battery terminal with an instrument; one of the conducting members being provided with a conductor-receiving socket, a wedge face, and an interior opening a wall of which constitutes a jaw; the other conducting member being provided with a cooperating wedge face, and with a cooperating jaw; the wedge faces being adapted to engage to effect a relative sliding movement of the two conducting members into clamping engagement with the storage-battery terminal; the clamping walls of the jaws extending at right angles to the direction of relative sliding movement of the conducting members; the said other conducting member having an opening that is elongated in the direction of relative sliding movement of the jaws and that is situated to one side of the clamping jaws; the said one conducting member having a screw-threaded opening registering with the elongated opening; and a screw-threaded member mounted in the elongated opening, and screw-threaded into the screw-threaded opening, and provided with a polygonal head adapted to be engaged by a wrench to effect the said relative sliding movement of the conducting members into clamping engagement with the storage-battery terminal.

In testimony whereof, I have hereunto subscribed my name this twenty-fourth day of October, 1919.

CHARLES MELVIN DAVIS.
